TOY PROJECTILE

Arthur Grodde, Laurentian View, Ontario,
Canada

Application September 6, 1941, Serial No. 409,897

1 Claim. (Cl. 46—200)

This invention relates to toy projectiles and more particularly to a toy projectile adapted to produce an explosion upon contact with the ground or other surface.

The principal object of this invention is the provision of a toy projectile which is adaptable to receive a percussion cap within a recess in the base and having a hammer or firing device associated therewith arranged to strike the percussion cap and cause same to explode when the projectile is thrown upon a surface.

Projectiles of this character being known in the art, the more particular objects of this invention include the provision of a device of the type set forth which is extremely simple to manufacture and assemble; which will retain the percussion cap in position at all times and which have a positive action.

Another object is to provide a toy projectile which will emit a sound while travelling through the air until the impact is made. Other objects of a more general nature are to provide an inexpensive, durable and efficient invention of the character set forth.

With the above noted and other objects in view which may appear as the description proceeds the invention resides in the novel construction, combination and arrangement of cooperating parts as hereinafter more specifically set forth, claimed and shown in the accompanying drawing forming part of this application, and in which:

Fig. 1 is a pictorial view of the invention.

Fig. 2 is a sectional view thereof.

Fig. 3 is a modification of the invention, and

Fig. 4 is a plan view of the base.

Referring more in detail to the drawing in which similar reference characters designate corresponding parts throughout the several views it will be seen that the invention consists of a metal base 10, having a substantially conical nose 11, to simulate a shell or bomb nose.

A cone shaped recess 12, in the upper end of the base 10, has a shaft 13, concentrically disposed therein in fixed relation thereto. Upon the said shaft the hammer 14, is slidably arranged. The said hammer consists of a solid metal body having a bore 15, centrally disposed therethrough, the bore 15, is slightly larger than the diameter of the shaft 13, so that a loose, sliding fit is obtained. The lower extremity of the hammer is cone shaped as indicated at 16, to fit snugly within the cone shaped recess of the base 10.

A stop 17, is secured to the shaft 13, to limit

the movement of the hammer 14. Any suitable retaining means may be employed for this purpose. For example the shaft may be crimped or widened at this point for the purpose of limiting the movement of the said hammer. A flag as indicated at 18, may be placed on the free extremity of the shaft or any other suitable emblem or the like may be employed.

To operate the device a percussion cap 19, is placed within the conical recess when the hammer and base are spread apart. The projectile is then thrown in the air or against an obstruction, the forward movement causing the hammer to abut against an adjustable stop 17, until the nose or base is brought to a sudden stop when it strikes an object with the result that the hammer is given impetus to violently strike the base thereby firing the percussion cap disposed therebetween in the recess 12.

It will be noted that the conical recess operates to hold the percussion cap 19, therewithin at all times, including that period in which the hammer and base are apart. It may be found practical to provide the base of heavier metal than the hammer so that the hammer will abut the stop 17, when the projectile falls downward but it is believed that while desirable it is not necessary.

In the modification of Figs. 3 and 4, the principle and method of attaching the base 20, and hammer 21, to the shaft 22, is the same; a stop 23, is also provided. The said base 20, has an annular flange 24, which forms a cup like recess in the top surface. The said recess is further enhanced by an annular groove 25, into which the percussion caps tend to slide when the said percussion caps are placed in the recess.

The bottom of the hammer 21, is provided with an annular projection 26, of substantially the same size as the groove 25, which operates to strike the percussion cap within the groove 25, when the projectile strikes an object.

The flange 24 which extends radially from the base is provided with a series of spaced slots 27 which permit the flames and smoke of the exploded cap to escape. From the foregoing it is apparent that I have provided an extremely simple and durable article of manufacture as and for the purpose set forth.

It is believed that the construction and advantages of the structure shown will be apparent from the foregoing paragraphs taken in conjunction with the accompanying drawing without further detailed description.

While the preferred embodiment of the inven-

tion has been disclosed it is understood that minor changes in the details of construction, combination and arrangement of cooperating parts may be resorted to within the scope of what is claimed without departing from the spirit of the invention.

I claim:

A toy projectile comprising a base member, a shaft disposed axially of the base member and extending upwardly therefrom, an annular groove formed in the top surface of said base member

5 in spaced concentric relation to said shaft adapted to receive a percussion cap, and a hammer slidably mounted on said shaft having an annular projection on its lower end adapted to interfit in said groove whereby the cap is exploded when the projectile strikes an object, the outer wall of said groove having a series of spaced slots therein opening through the outer wall of said base member for the expulsion of gases from said 10 groove.

ARTHUR GRODDE.
